UNITED STATES PATENT OFFICE

CLANCY R. CURTIS, OF ST. PAUL, MINNESOTA, ASSIGNOR OF ONE-HALF TO CHARLES E. BRUNS, OF ST. PAUL, MINNESOTA

FEATHER RENOVATOR

Application filed January 25, 1929. Serial No. 335,021.

My invention relates to a feather renovating device and the main object is to provide a simple, highly efficient device, the use of which separates dust, dirt, loose quills and 5 any foreign matter from the feathers and delivers the latter in a desirable fluffy and clean condition.

Further objects and advantages are hereinafter fully set forth and the preferred construction of the device is illustrated in the accompanying drawings, in which,—

Fig. 1 is a plan view of my feather renovator mounted on a portable platform.

Fig. 2 is a front view of Fig. 1.

Fig. 3 is an enlarged longitudinal sectional elevation approximately as on line 3—3 in Fig. 1, showing mainly the interior construction of the feather circulating passages of the main drum.

Fig. 4 is a left hand end elevation of Fig. 2, a portion of the upper part of the drum being broken out to reveal a rear air current guide; also showing a modification involving an outlet spout.

Referring to the drawings by reference numerals, 5 designates a platform which may be either portable or fixed, said platform having mounted at one end a suitable rotary blower, 6 with a driven pulley, 7 engaged by 30 a belt, 8 also engaging a driving pulley, 9 of a motor, 10 also mounted on the platform in proximity to the blower. 11 is a receiving hopper near blower 6 and communicating with the latter by a conductor pipe 12 and 13

35 is a delivery spout from any suitable container (not shown) to deliver feathers into hopper 11. 14 is the outlet pipe of the blower, the rotary motion of the blower being such as to draw the feathers from the hopper and discharge them through pipe 14 at a high previously determined velocity (as indicated by arrows 15) into the receiving duct 16 entering the lower part of a large upright drum 17 which will now be described.

40 The drum 17 comprises preferably an upright hollow sheet metal drum mounted on platform 5 in alinement with the outlet spout 14 of the blower.

The face or perimeter of the drum is designated 45 17A, the rear wall 17B and the front

wall 17C; 17A being of course circular and inwardly of the face 17A is another fixed circular partition 18 concentric to 17A forming thus a circular duct 19, the lower part of which communicates directly with the intake 55 duct 16 from the blower 6. The top wall of said duct 16 (designated as 16T) inwardly of face 17A forms a cross wall in the lower part of the drum and the inner partition 18 terminates in spaced relation above said wall 60 and may be curved inwardly and thence upwardly as 18C (Fig. 3), thus providing a passage-way 20 opening into the center of the drum.

In Fig. 3, 21 designates, in dotted outline, 65 a quadrangular outlet opening in the front wall 17C of the drum communicating directly with a large sheet metal duct 22 extending forwardly and downwardly toward the base or platform 5 where it is formed as an enlarged horizontally disposed receiving chamber designated 22C. From this chamber extends an outlet spout 22S terminating in an outlet pipe 23 as in Fig. 4. In pipe 23 a suitable valve 24 is operable to let out renovated 70 feathers which may simply drop into a rack (not shown) under said pipe.

The receiving chamber 22C is preferably provided with a drawer 25 to catch heavy particles gravitating thereinto and being further guided into the drawer by sloping partitions 26 in said chamber (see Fig. 4).

In Fig. 4 and also in Fig. 3 the upper portion of the rear wall 17B of the drum is shown curved inwardly as 17B just below the inner 85 circular wall 18, this to guide the feather carrying current of air as will be now set forth.

In Fig. 2, 36 is an aperture in the plane of wall 17C between housing 22 and the upper curvature and covered by a screen 27 for outlet of air. (See also Fig. 2.)

In the use of my device feathers to be renovated are put in hopper 11, the blower 6 drawing the feathers into it and blowing them with considerable force through conduit 16 into the circular conduit 19, the feathers being subject of course to the strong air current therein and moving as indicated by arrows 28 to and through aperture 20 into 100

the center chamber of the drum. The feathers in the latter chamber are in motion and suspended and continue to move through the aperture 21 and into the housing 22 losing 5 considerable momentum because the main air current finds outlet through screen 27. Subsequently the feathers drop downwardly in housing 22, the light and desirable feathers gravitating in semi-suspension as the short 10 quills, sand and heavier foreign matter drop toward the bottom and fall into the pan 25. The renovated feathers continue on beyond the pan, however, as indicated by arrow 29 (Fig. 4) thence into and through the discharge means described. The arrows 30 in 15 Fig. 3 indicate the path of movement of the feathers from the center of the drum through aperture 21 to the housing or container 22.

The use of my device has been fully 20 closed but it might be added that the centrifugally moving air currents loosen all foreign matter, dust, etc., from the feathers and the feathers delivered from the device are always in a highly satisfactory condition for 25 use in pillows, mattresses and other stuffed articles.

I claim:

1. A feather renovating device comprising 30 a power blower, a drum mounted in an upper right plane, a perimetral duct in said drum and a tangential extension thereof communicating with said blower, said perimetral duct provided with outlet means from the center of the drum, and said blower arranged to 35 receive and project feathers to be renovated into said perimetral duct by air pressure and from said duct into the central part of the drum, elevated outlet means from said central part of the drum comprising a settling 40 duct directed outwardly and downwardly therefrom, a means for reducing the air current at said drum outlet, said settling duct adapted to receive the feathers in semi-suspension and guide means therein to guide 45 heavier matter to the bottom part of it and further to guide the feathers beyond said bottom part to a discharge means.

2. The structure specified in claim 1, in 50 which said latter discharge means comprises a suitable outlet pipe above the base of said settling duct and a valve in said latter outlet.

3. The structure specified in claim 1 in 55 which said means for reducing the air current at the drum outlet comprises the provision of an opening adjacent said outlet in a wall of the drum and a screen suitably mounted in said opening.

4. The structure specified in claim 1 in 60 which said means for reducing the air current at the drum outlet comprises the provision of an opening adjacent said outlet in a wall of the drum and a screen suitably mounted in said opening and the opposite wall 65 from said apertured wall formed with an

inwardly directed slope arranged to guide air currents to and through said screened aperture.

In testimony whereof I affix my signature.

CLANCY R. CURTIS.
